United States Patent Office

Des. 189,153
Patented Nov. 1, 1960

189,153

PRESSING UNIT

Ernest Davis, Syracuse, N.Y., assignor to Ward Industries Corporation, Syracuse, N.Y., a corporation of Delaware

Filed Feb. 8, 1957, Ser. No. 44,804

Term of patent 14 years

(Cl. D49—1)

FIG.1

FIG.2

Figure 1 is a front perspective view of the pressing unit. The side of the pressing unit opposite that shown is the same in appearance as the side shown, and the back of the unit is plain.

Figure 2 is a front elevational view of the pressing unit.

I claim:

The ornamental design for a pressing unit, as shown and described.
